UNITED STATES PATENT OFFICE.

THADDEUS F. BAILY AND FRANK T. COPE, OF ALLIANCE, OHIO, ASSIGNEES TO THE ELECTRIC FURNACE COMPANY, OF ALLIANCE, OHIO, A CORPORATION OF OHIO.

HORIZONTAL SHELL-ROLLING MILL.

1,353,982.

Specification of Letters Patent. Patented Sept. 28, 1920.

Application filed June 14, 1918. Serial No. 240,057.

To all whom it may concern:

Be it known that we, THADDEUS F. BAILY and FRANK T. COPE, citizens of the United States, both residing at Alliance, in the county of Stark and State of Ohio, have invented a new and useful Horizontal Shell-Rolling Mill, of which the following is a specification.

This invention relates to horizontal rolling mills and more particularly to a mill of this class designed especially for rolling artillery shells.

The object of our invention is to construct a device of this character that will accurately roll and pierce steel shells simultaneously.

Another object is to so construct a device of this character that two shells of the same caliber can be rolled at the same time, thereby greatly reducing the time necessary to manufacture a shell and proportionately reducing the cost of manufacture.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

In the drawings:

Figure 1 is a plan view of our device.

Fig. 2 is a longitudinal section therethrough showing two substantially finished shells upon the piercing bars.

Fig. 3 is a transverse section.

Fig. 4 is a longitudinal sectional view through a modified construction of our shell rolling mill.

Fig. 5 is a transverse section through Fig. 4.

Similar numerals of reference indicate corresponding parts throughout the several figures of the drawings.

In the construction of our horizontal shell rolling mill, upon the bed 1 are a pair of standards 2, disposed in alinement and opposite each other, at one end of the machine and a similar pair of standards 4 is ar-

ranged in alinement at the opposite end of the machine. Extending transversely of the machine and between each pair of standards is a raised portion 5, the upper face of which is beveled upon its edges. Supported upon each pair of standards 2 and 4 and in direct alinement above the raised portion 5 is a transverse beam 6 which is beveled upon its lower face and slidably mounted between each raised portion 5 and its corresponding beam 6 is a pair of sliding bearing blocks 7 and 7'. Secured to each of the bearing blocks 7 and extending outwardly therefrom is a screw shaft 8 and upon each of the shafts 8 is mounted a gear 9 which is internally threaded at its hub, the said threads fitting the threads upon the shafts, the gears 9 meshing with gears 10 which are mounted upon and adapted to rotate with a pair of overhead shafts 11. Each of the shafts 11 carries upon one of its ends a beveled pinion 12 which meshes with a similar pinion 14 fixed to a shaft 15. Suitable gearing is arranged to rotate the shaft 15 from a motor 16. All of the foregoing mechanism is of the usual construction, common to rolling mills known as the "screw down" mechanism.

In each of the bearing blocks 7 is rotatably mounted one journal of a roll 17, the opposite journal of each roll being similarly mounted in one of the bearing blocks 7' at the other end of the machine. It will be seen that when current is fed to the motor 16 to drive it in one direction, rotation of the shaft 15 will cause the gears 9 and 10 to be rotated through the pinions 12 and 14, and the rotation of the said gears 9 by virtue of their internally threaded hubs will cause the shafts 8 to be fed inward and likewise opposite rotation of the motor 16 will cause the shafts 8 to be withdrawn. The bearing blocks 7 and 7' being secured to the shafts 8 and slidably mounted between the raised portions 5 and the beams 6 will likewise be moved toward and away from the longitudinal center line of the machine through the operation of the motor 16.

Secured at either end of the machine upon the raised portions 5 and in the transverse center thereof are brackets 18, which form supports for bearings 19 and in each of said bearings is slidably mounted a piercing bar

20 which is pointed upon its inner end as shown in Fig. 2. The piercing bars are arranged upon the exact transverse center of the machine and in line with the horizontal 5 center of the rolls 17. The piercing bars extend outwardly in a longitudinal line from the machine, their outer portions being threaded as shown at 21. A standard 22 is arranged at either end of the machine.

10 But one such standard is shown upon the drawings, the machine being broken away at the opposite end, the other standard however being an exact duplicate of the one illustrated. A shaft 24 extends through 15 each standard 22 and is driven by a motor 25 and a worm 26 carried by the shaft is arranged to mesh with a worm gear 27 which is journaled within the standard 22. The worm gear 27 is internally threaded to 20 fit the threads upon the portion 21 of the piercing bars. A jam nut 28 is screwed upon the threaded portion 21 of each of the piercing bars to a predetermined point and is then secured within a block 29 which is 25 arranged to slide upon a guide 30 secured between the portion 5 and its corresponding standard 22 at either end of the machine. The piercing bars are thus held against rotation when the worm gear 27 is rotated.

30 It will be obvious that when the motors 25 are rotated in one direction the worm gears 27 will be driven from the worms 26 and by reason of the internally threaded portion of the worm gear meshing with the 35 threads upon the portion 21 of the piercing bars will cause the said piercing bars to be fed inwardly and reverse motion of the motor 25 will likewise cause the bars to be withdrawn. Extending transversely be- 40 neath the machine at the longitudinal center thereof is a shaft 31 extending from a motor 32. Mounted upon the shaft 31 is a worm 34 which meshes with a worm gear 35. The worm gear 35 is mounted upon a stub shaft 45 36 which is carried by bearings upon a standard 37, and at either end of the stub shaft 36 is fixed a beveled pinion 38 which mesh with beveled pinions 39 mounted in bearings 40. The pinions 39 are internally 50 threaded and fit upon screws 41 which carry upon their upper ends a V-shaped trough 42. The trough 42 extends longitudinally of the mill, its center line being in the exact transverse center of the mill. Rotation of 55 the motor 32 in one direction, will, through the worm 34 and worm gear 35 cause the stub shaft 36 to be rotated, which obviously rotates the pinions 38 and drives the pinions 39 therefrom causing the screws 41 to be fed 60 upwardly and to raise the trough 42. Reverse motion of the motor 32 will likewise cause the trough to be lowered.

Extending beneath the base of the machine 1 and slightly at one side thereof is a 65 shaft 44 from a motor 45 and mounted upon

this shaft is a pair of pinions 46 arranged to engage pinions 47, each of the pinions 47 being fixed upon a vertical shaft 48. Each of the shafts 48 carries near its lower end a sprocket 49 and near its upper end a similar sprocket 50. Mounted in standards 51 in direct transverse horizontal alinement with each of the sprockets 49 is a sprocket 52 which is adapted to be driven by a sprocket chain 53 connecting with its respective sprocket 49. Mounted in suitable bearings and in direct vertical alinement with each of the sprockets 52 are similar sprockets 54, which are arranged in horizontal alinement with the sprockets 50 and 75 are adapted to be driven by sprocket chains 55 co-operating with the said sprockets 50 as shown. The sprockets 52 are internally threaded and fit upon threaded shafts 56, the upper extremity of each of the shafts 56 being bifurcated and forming bearings 80 for cutter disks 57. The sprockets 54 are similarly internally threaded and fit upon threaded shafts 58, the lower ends of the shafts 58 being bifurcated to form bearings 85 for cutter disks 59. It will be seen from the foregoing that when the shaft 44 is driven in one direction by the motor 45, the vertical shafts 48 will be rotated and drive the chains 53 and 55 which in turn will rotate 90 the sprockets 52 and 54 and by virtue of the threaded interiors of the said sprockets meshing with the threads upon the shafts 56 and 58 will cause the said shafts to be fed inwardly and to move the cutters 57 100 and 59 toward the center line of the machine.

The rolls 17 as shown, are each formed with an enlarged annular portion 60 at its longitudinal center; the cylindrical portion 105 of each roll upon each side of the enlarged portion curving outwardly and describing the curve upon the forward end of the exterior of an artillery shell.

The rolls 17 will be driven by any ordinary and well known roll driving mechanism, the couplers 61 between the rolls and the said driving mechanism being shown at the left of Fig. 1. Each of the rolls 17 will be rotated in the same direction.

In the operation of our shell rolling mill the roll rotating mechanism will be put in operation to drive the rolls. The motor 16 will then be rotated to feed the shafts 8 outwardly and space the rolls apart. The 120 motor 25 will then be operated to move the piercing points 20 into out-drawn position. The V-shaped trough 42 is now lowered with the operation of the motor 32 and a billet containing a sufficient quantity of 125 heated steel to form two artillery shells is then placed in the trough 42. The motor 32 is then operated to lift the trough until the billet of steel has come into direct horizontal alinement with the centers of the 130

piercing points 20 and the rolls 17. The motor 32 is then stopped holding the trough 42 thus elevated. The motor 25 is then again operated, this time in the direction to feed the piercing points 20 inwardly, the said points advancing until they have just begun to engage the opposite ends of the billet of heated steel. The motor 25 is then stopped temporarily and the motor 16 operated to move the rotating rolls 17 inwardly. As soon as the annular extensions 60 upon the rolls come into contact with the billet of steel and begin to turn it, the motor 32 is again operated to lower the trough 42. The motor 25 is now again operated to feed the piercing points 20 inwardly and as the said points advance the rolls 17 are rolling the billet of steel into the form of two shells with their points together. The exterior of the shells is thus shaped while the piercing points are forming the explosive charge cavity. When the shells have been exactly and accurately formed the rolls 17 are once more drawn apart and the motor 45 operated to advance the cutter disks 57 and 59 which trim the shells to the exact length required. The cutters are then withdrawn and the motor 25 operated to withdraw the piercing points. The rolled shells are then removed and severed at the longitudinal center.

It will be seen that by our process artillery shells can be manufactured with extreme rapidity effecting an enormous saving of time and labor over the present processes of making shells. It will also be seen that by the rolling process the effect upon the steel will be to wrap the grain of the steel and cause it to run substantially spirally of the shell.

In Figs. 4 and 5 we have illustrated a slightly modified form of our shell rolling mill in which we employ three rolls shown at 65. The piercing rods 66 as shown in Fig. 5 are positioned centrally between the three rolls, which are equidistantly spaced to form a triangle. In this form of mill the necessary mechanism for feeding the piercing points inwardly and outwardly is employed. The two lower rolls in this mill are mounted on stationary bearings and not designed to slide. The upper roll however is carried in the sliding bearings 67 in which are secured threaded shafts 68 which cooperate with internally threaded pinions 69 meshing with pinions 70 on the shaft 71. A motor 72 is employed to drive the shaft. In the operation of this type of mill the motor 72 is rotated to raise the upper roll. The billet of heated steel is then dropped upon the two lower rolls, the piercing points advanced and the upper roll lowered into contact with the billet.

Having fully described our invention what

we claim as new and desire to secure by Letters Patent, is:

1. In a device of the character described, a plurality of rotating rolls shaped to form the exterior of two artillery shells, the said rolls being adapted to have placed therebetween a billet of heated steel and means for moving the said rolls into engagement with the said billet and to roll it into the form of artillery shells and piercing rods slidably mounted to enter the said billet from opposite sides and to form therein cavities while the said billet is being rolled, the said cavities being in the form of explosive charge chambers in finished artillery shells.

2. In a device of the character described, a plurality of rotating rolls, the exterior of said rolls forming the exterior of a pair of artillery shells, the said rolls being adapted to have placed therebetween a billet of heated steel, means for moving the said rolls into engagement with the said billet to roll it in the form of a pair of artillery shells, piercing rods slidably mounted and means for advancing said piercing rods to form explosive charge chambers within said artillery shells as they are being rolled.

3. A shell rolling mill including, a plurality of rotating rolls adapted to coöperate and shaped to form a billet of steel in the form of two artillery shells and piercing rods arranged to enter said billet from opposite ends and form therein explosive charge cavities while the billet is being rolled.

4. A shell rolling mill including, a plurality of rotating rolls, means for positioning a billet of steel between and in the plane of the horizontal centers of the rolls, means for moving the rolls into engagement with the billet, the said rolls being shaped to form the billet into artillery shells, piercing rods arranged to enter the billet from opposite ends while the billet is being rolled to form therein explosive charge cavities, and means for trimming the shells to the required length.

5. A shell rolling mill including a plurality of rotating rolls shaped to form the exterior of two artillery shells, the said rolls being adapted to have placed therebetween a billet of heated steel, means for moving the rolls into engagement with the billet and to roll it into the form of two artillery shells, piercing rods slidably mounted to enter the billet from opposite ends to form cavities therein while the billet is being rotated and means for trimming the shells to the required length.

In testimony that we claim the above, we have hereunto subscribed our names.

THADDEUS F. BAILY.
FRANK T. COPE.
